MACHINE FOR DRYING TEXTILE FABRICS IN OPEN FORM.

1,237,972.

Specification of Letters Patent. Patented Aug. 21, 1917.

Application filed October 21, 1916. Serial No. 126,962.

To all whom it may concern:

Be it known that I, CHARLES TAYLOR, a subject of the King of Great Britain, residing at Wilmington, in the county of New Castle and State of Delaware, have invented a new and useful Machine for Drying Textile Fabrics in Open Form, of which the following is a specification.

The object of my invention is to provide a machine for drying textile fabrics in open form, which is used more especially for drying the so-called anilin black dyed material, the machine being designed to eliminate the use of the customary drying cylinders or drums which subjects the material to a forced drying action and results in weakening the same as well as only allowing for but a superficial or imperfect dye thereto, which does not remain fast and permanent therewith; while my machine provides for a more natural drying action, in that the material inclosed and treated in the same is directly subjected to the influence of a hot air blast which circulates within the machine and is brought into direct contact with the material which is loosely hung and supported in vertical layers upon a great plurality of parallel and transverse hanging-rollers, said rollers being rotatably mounted upon coacting endless conveyer belts which keep them moving continuously within the machine from one end thereof to the other in a circuit. The wet material entering the machine is automatically folded in layers upon the successive hanging-rollers as the same are advanced by the receiving end of the machine and is transferred from one hanging-roller to the other consecutively by virtue of the rotating action of the same while the hanging-rollers are being simultaneously conveyed across the machine and toward the delivery end thereof, where the material is finally delivered in a dry condition. The machine may be built with dimensions suitable to permit of the housing of a substantial quantity of material, every part of which is at all times while in the machine surrounded by the hot air contained therein which slowly and thoroughly dries the material between the intervals of entering and leaving the heating chamber of the machine, so that each element of the draft of material passing through the machine is kept under the influence of the hot air blast circulating therethrough from the time it enters the ma-

chine until it leaves it, and the duration of time between same can be made to suit conditions by speeding up or slowing down the conveying and advancing mechanism of the apparatus, or by varying the degree of temperature and velocity of the hot air blast introduced into the machine, according as may be desired.

Another object is to provide a drying and oxidizing machine, especially for drying anilin black dyed goods, which dries the material by a natural drying method and is capable at the same time of handling and drying a greater quantity of material in a given length of time than what can be claimed by the use of the ordinary cylinder driers which provide for forced drying. The machine is extremely simple and efficient and affords the material treated therein every advantage possible for possessing fast and permanent coloring, attended by live luster, and also keeps the material free from creases and tender spots. These conditions are not found existing in material treated by the forced drying cylinder heating method, which, to the contrary, leaves the material without a natural luster, full of creases, breakouts, tapes, and tender places, and at best only provides a superficial and imperfect dye which is easily rubbed off and readily greened.

Another object is to provide a drying machine for anilin blacked dyed material, which will handle and treat cottons, silks, or mixtures of cotton and silks to equal advantage, in that the slow and natural drying feature embodied in the machine along with the conveying feature thereof, affords the material every opportunity to dry naturally, according to the requirements of its peculiar constituents, so that in the case of drying material consisting of a mixture of silk and cotton, the same may be handled with much better results than can be obtained by the use of the cylinder forced drying method which treats with the two elements of the mixture, namely, the silk and cotton, (so far as the degree of heat and the length of time to which it is subjected to heating is concerned) in exactly the same manner,—it being a known fact that in mixed materials the cotton and silk fibers require different temperatures to dry them—that is to say, while silks require a low temperature, as low as 80° F., cotton will dry at any

temperature up to 200° F., so that in my machine the low temperature required for drying the silk will sufficiently dry the cotton as well, since the material is allowed to remain subjected to the hot air blast in the machine an ample length of time to assure perfect drying of both the fiber elements of the mixed material. Therefore, in that regard my machine is far better adapted to treat such materials than the other method of using cylinder driers, which, because of the forced and rapid drying features inherent in the same, invariably results in over or under treating one or the other of the elements in an effort to treat the other.

Another object is to provide a machine used more particularly for drying dyed fabrics, which is supplied with hot air of a desired temperature circulating therethrough at a desired velocity, and is provided with a continuously moving conveyer and hanger member which is adapted to hang the material thereupon in separate layers and to simultaneously advance the same through the machine successively from one hanger to another; thus keeping the hangings of fabrics which are stretched out open thereon in vertical motion as well as in horizontal motion,—the former being due to the rotating of the hangers, while the latter is due to the horizontal traveling of the conveyer member.

Still another object is to provide a machine for air drying anilin black dyed cloths coming directly from the dyeing bowl and through the squeezing rollers thereof,—the machine being designed to inclose the material within the same in a manner which relieves it from tension and yet keeps it in motion with every part thereof at all times properly stretched open and subjected to circulating hot air contained in the machine and maintained at proper temperature and velocity.

To these as well as other ends my invention consists of the novel features of construction, combination, and arrangement of parts set forth in the following specification, and particularly pointed out in the subjoined claims.

Referring to the accompanying four sheets of drawings,—

Figure 1 represents a diagrammatic and part sectional and elevational view of my drying apparatus, and shows the same receiving the goods coming from the other machinery of the dyeing plant.

Fig. 2 represents an enlarged view of the transferring and lapping device used for guiding the material on to the successive hanging-rollers of the machine as the same are conveyed by and under said transferring rollers.

Fig. 3 represents a plan view of the drying machine, showing the top of the same

removed therefrom, with the machine working on two drafts of material *m* and *m'*.

Fig. 4 represents a sectional view taken on line 4—4 in Fig. 1 looking in the direction of the arrows, showing the endless conveying platform used at the bottom of the machine for supporting the hangings and pleats of material.

Fig. 5 represents an elevational view showing the driving side of the machine, which is the opposite side to that shown in Fig. 1.

Fig. 6 represents the delivery end of the machine, showing the same with the casing removed therefrom.

Fig. 7 represents a perspective view of a link used in the conveyer-belts for supporting the rotatable hanger-rollers.

Fig. 8 represents a sectional view taken on line 8—8, Fig. 1 looking in the direction of the arrows, showing the hangings of the material being conveyed through the machine and also the guide-wall which is partly broken at various sections thereof for showing the mechanism behind the same.

Fig. 9 represents an enlarged view of the upper right-hand corner of Fig. 8, showing a modification thereof, the hanging-rollers being supplied with sprocket-wheels which are driven by an endless chain for rotating the hanging-rollers, at the desired speed, simultaneously with their being conveyed laterally along the machine and independent of the lateral traveling speed of the same.

Fig. 10 represents a diagrammatic sectional view showing the application of the sprocket-wheels on the hanging-rollers of the device as shown in Fig. 9 and the driving mechanism therefor.

Fig. 11 represents the same view as Fig. 9 but shows another modification in using a worm wheel for rotating the hanging-roller of the device, instead of the sprocket-wheel and chain used in Figs. 9 and 10.

Fig. 12 represents a part sectional view showing the application of the worm and worm wheel used in Fig. 11.

Fig. 13 represents a sectional view taken on line 13—13, Fig. 9, showing a modification of the guide-rollers used for preventing the conveyer-belts, supporting the supporting-rollers, from sagging in the machine.

Like numerals refer to like parts throughout the several views of the drawings.

The numeral 1 in its entirety represents the machine casing which may be made up of wood or metal or both according as may be desired and may be, if desired, lined as indicated in Fig. 9 or covered as indicated in Fig. 11 with asbestos, or other suitable non-heat-conducting material, for retaining the heat of the dry air introduced within the casing, and may be provided, as shown in Fig. 3, with a suitable number of removable sections 2 around the sides or at the top

thereof, for premitting access to the interior of the casing of the machine. Within the casing 1 is the endless cloth supporting and hanging conveyer, which in the main consists of the two co-acting endless linked-belts 3 and 4, which rotatably support the parallel and transverse supporting and hanging-rollers 5 in the bearings 6 provided in the links 7, Fig. 7, of the belts 3 and 4 for the purpose.

The co-acting linked-belts 3 and 4 are supported in operating position on the sides 8 and 9, respectively, of the machine, on the supporting and driving sprockets 10 and 11 positioned in the upper sections of the casings and near the sides 12 and 13, and are supported upon the driving shafts 14 and 15 which project through the casing on the driving side 9, and are preferably coupled with the bevel-gears 16 and 17, which engage with the driving-gears 18 and 19, respectively, for driving the gears 16 and 17 in the same direction, as is indicated by the arrows marked "d" in Figs. 1 and 5. The co-acting linked conveyer-belts 3 and 4 are guided preferably at the bottom of the casing by the idler and guide-rollers 20, which may be rotatably supported on the shafts 21 and permitted to run freely on said shafts or may be secured thereto and allowed to rotate therewith, or the rollers 20 may be substituted by using sprocket-wheels similar to those used at the top of the casing for driving the linked belts, if desired. 22 is an endless conveyer-platform which is supported upon suitable rollers or cylinders 23 toward the bottom of the casing and above the lower section of the conveying and hanging rollers 5, as is shown in Fig. 1, and may be made up of wood laps or lattice, or of any other suitable material. The rollers or cylinders 23 may be supported upon shafts 24 which are driven by the gears 25 which rotate in the direction of the arrows marked "g" (Fig. 5) which is the same direction assumed by the gears 16 and 17 for causing the endless conveying-platform 22 to travel in the same direction as the endless co-acting linked-belts 3 and 4 of the device.

26 and 27 are end-guide-walls which inclose the materials being conveyed through the machine and which prevent them from coming into contact with the apparatus thereof, as is shown in Fig. 1, and may be suitably perforated to allow the hot air to circulate therethrough if desired. 28 is an ordinary blower which sucks in dry air through the pipe 29 and blows and forces the same into the machine through the pipes 30 which branch off into the small transverse discharge pipes 31 which extend clear across the machine, as is shown in Figs. 3 and 6, and which are provided with longitudinal slots, or other such perforations, for discharging directly within the casing of the

machine and upon the material being conveyed therethrough, as is indicated by the streams suggested in Fig. 1.

32 represents the outlets for the hot air from the interior of the drying chamber in the machine. 33 represents the conventional type of nip-rollers which are suitably connected to be driven at the required speed for drawing the material "m" into the machine, as is shown in Figs. 1 and 2, and may be driven by the main driving-shaft 34 of the machine, or otherwise, according as may be desired. 35 are the transfer-rollers which are preferably provided with yielding outer covers 36 of rubber, felt, or other such suitable material, and which are secured to the shaft 37, which is in turn rotatably mounted in suitable bearings to rotate freely when necessary, as when the same is brought into frictional contact with conveying and hanging rollers passing it as they are being conveyed through the machine. The material "m" coming from the padding machine 38 may be passed over a series of the ordinary drums or drying cylinders 39, as shown in Fig. 1, if desired, and is admitted into the machine through the opening 40 provided therefor on the intake or receiving end 12, and is drawn out of the machine through the discharge or delivery opening 41 provided therefor in the top of the same toward the delivery end 13 of the machine, and is passed over the guide-roller 42, wherefrom the same may be delivered into a delivery truck, or elsewhere if desired.

The conveying and hanging rollers 5, which are rotatably mounted in the bearings 6 of the links 7 of the co-acting conveying-belts 3 and 4, may be provided at the ends thereof (as is shown in Fig. 6) with the guide and turning wheels 43 which are allowed to ride on the supporting tracks 44 (Figs. 8 and 12) supplied at the top of the machine and curved at the ends 45 to permit the wheels 43 to ride on to the same as the conveyer-belts are being advanced along the machine at the top thereof; thus supporting the conveying and hanging rollers 5 and preventing the same from sagging, and at the same time imparting to them a turning motion which is independent of the lateral motion thereof and is brought about by the frictional engagement of the rollers 43 engaging with the tracks 44—the rate of speed of the turning motion of the supporting-rollers 5 depending upon the diameters of the wheels 43.

Fig. 9 shows a modified mechanism employed with the hanging rollers 5 for providing a positive turning drive for the same where a higher speed of rotation is required for the rollers 5 than can be obtained from the frictional drive shown in Figs. 6 and 8—the modification lying in the use of the sprocket-wheel 46 which is secured to the

shaft of the roller 5 and is adapted to rotate therewith, the sprocket-wheel 46 being supplied at either end, or on both ends, of the hanging and conveying roller 5, and the 5 shafts of the rollers 5 may also be supplied preferably with ball-bearing-supporting-rollers 47, which, when the hanging-roller 5 reaches the top of the machine, are allowed to ride on the tracks 44 (preferably supplied 10 on either side of the machine) for preventing the conveyer-belts 3 and 4 from sagging. The sprocket-wheels 46, when reaching the top of the machine, are brought into engagement with the endless-sprocket-chain 48 15 which is supported upon the guide-rollers 49 and is driven by the driving-sprockets 50, and are caused to move in the direction of the arrows marked "a", Fig. 10 for turning the sprockets in the direction of the arrows marked "b" while the same are being laterally conveyed in the direction of the arrow marked "c" on the co-acting link-belts 3 and 4 which are advanced simultaneously to keep the hanging-rollers carried thereby 20 parallel and at right angles thereto, around the machine in the direction of the arrows marked "c", Fig. 1, by the operation of the driving-wheels 10 and 11 which turn in the direction of the arrows marked "d". The 25 driving-sprockets 50 may be suitably connected and driven by the driving-shaft 34, or in any other suitable manner, and may be driven at any desired speed to permit the hanging-rollers 5 to have a turning motion 30 of the required speed, independent of the rate of lateral travel that is imparted to the same by the speed of the co-acting link-belts 3 and 4, which convey the same within the 35 machine.

40 Figs. 11 and 12 represent another modified form of mechanism used for imparting turning motion to the hanging-rollers 5 which are carried by the co-acting linked-belts 3 and 4, in which case the use of the worm 51 and worm wheel 52 are resorted to 45 in place of the frictional drive suggested in Fig. 8, or the sprocket and chain-drive suggested in Figs. 9 and 10. The rollers 5 in this case are supplied with pinions 52 in place of the sprockets 46, and in place of the sprocket-chain 48 the worm 51 is used 50 to drive the pinions 52, as shown in Figs. 11 and 12, for accomplishing the same result, namely, turning the supporting-rollers 5 at 55 any desired speed, while the same are being laterally conveyed on the co-acting conveyer-belts 3 and 4 of the machine. There again, a ball-bearing type of roller-wheel 47 (Fig. 13) may be used for supporting the 60 rollers 5 when reaching the top of the machine and preventing the same from sagging, which at the same time permit the rotating action imparted thereto while they are being advanced in the machine laterally,—it being understood in using the roller or

ball-bearing type of guide-roller 47, that the shaft of the supporting-roller 5 being secured to the inner collar 53 is allowed to rotate therewith at any speed within the outer collar 54, between which are positioned the 70 roller or ball-bearings 55, so that while the collar 53, which is secured to the supporting-roller 5, may be rotating in the direction of the arrow marked "e" at any desired speed, the outer collar 54 may also rotate in the direction of the arrow marked "f" at the required speed at which the roller 47 is being advanced in the direction of the arrow marked "c" on the track 44. The driving shaft 34 which drives the supporting-roller-conveyer may be driven from the prime-mover by any suitable means, as by the belt 55 (Fig. 5) and may be geared, or otherwise suitably connected to rotate the platform-conveyer-drive-shaft 34 of the device, as by 80 the gearing shown in Fig. 5, which drives the gears 25 in the direction of the arrows marked "g" for causing the endless platform to travel in the direction of the arrows marked "h",—it being observed that such direction is the same as the direction of travel of the hanging roller-conveyer of the device. In Figs. 3 and 8, *m'* represents a second draft of material which is simultaneously handled and conveyed through the machine 95 in exactly the same manner as is done in the case of the material "*m*"; it being understood that the machine may be made wide enough to handle one or more drafts of material at the same time, according as may 100 be required.

Having thus described the parts of my invention in detail, the manner in which the same is employed is as follows:

It will be here understood that the speed 105 of travel of the auxiliary supporting conveyer platform 22 of the device, should be practically the same as the speed of travel of the hanging-roller conveyer-belt, or less if desired. The material coming from the 110 padding machine 38 may be directed directly into the machine, or may be allowed to pass over a series of drying cylinders 39 (5 or 6 in number), which cylinders are of the common type now used for drying purposes in dyeing plants, and may then be entered into the machine through the opening 40 between the nip-rollers 33, and in the first instance set with the end *M'* of the material pulled through the outlet or delivery opening 41, after which the machine may be started up. The machine thus started, sets into action the nip-rollers 33, the delivery and guide-roller 42, the co-acting belts 3 and 4 supporting the hanging-roller-conveyer in the direction of the arrows marked "c," the auxiliary conveyer and endless platform 22 moving in the direction of the arrows marked "h", the hanging-rollers 5 turning freely in the direction of the ar- 130

rows marked "b" (Fig. 1), and the blower 28 which forces hot air of the desired temperature into the machine. The outlets 32 of the machine are preferably supplied with 5 suitable dampers which may be used for regulating the discharge of the hot air from the chamber within the machine. The nip-rollers 33 are allowed to usher and draw into the machine the material "m" at the 10 desired rate of speed for allowing the material to work down between the two adjacent hanging-rollers 5 (dotted line Fig. 2) so that the same reaches the auxiliary platform conveyer and preferably rests 15 thereon a surplus amount of material which piles up in loose plaits or folds,—the auxiliary conveyer being preferably positioned at about a half dozen yards below the working hanging-rollers which are at the top of 20 the machine, so that the vertical hangings of material on the supporting hanging rollers 5 will be about six yards on each side thereof, and the surplus material piled on the auxiliary conveyer 22 (Figs. 1 and 8) 25 will be about four yards additional. And so the material is allowed to run between each set of adjacent hanging-rollers passing the receiving and transferring point of the machine at the top thereof. The hanger- 30 conveyer member at the top of the machine is continuously moving in the direction of the arrows marked "c" (Figs. 1 and 2) and is thus bringing consecutively into frictional engagement the hanging-rollers 5 35 with the transfer-roller 35 of the device, which guide and transfer the runs of material to shift from the advance side 5^a of the hanger-rollers 5 to the rear side 5^b thereof, as shown in Figs. 1 and 2; thus providing 40 a simple and automatic means of transferring and guiding the material into the hanging-rollers of the device; so that it will be observed that as the hanging-roller-conveyer advances along the top of the machine 45 with the rollers set apart equidistant on the co-acting belts 3 and 4, the material, when passing the nip-rollers 33, will run down on the advancing side 5^a of the rollers 5 until it reaches the transfer-rollers 35 and will 50 then run down the rear side 5^b of the roller and will keep running down, plaiting and folding when reaching the platform 22 until the adjacent and following hanging-roller comes into contact with the transfer-rollers 35, which operation is continually carried on as each and every supporting roller advances by and passes the nip and transfer rollers of the machine.

Now, while the hanging-roller-conveyer 60 and the platform-conveyer are advancing along the machine of an appreciable length at a comparatively slow rate of speed—say about 3 or 4 inches per minute—and are thus conveying the materials supported thereon laterally, that distance per minute,

it will be observed that the rotary action on the part of the hanging-rollers 5, which are forced to turn in the direction of the arrows marked "b" at any desired speed, naturally keeps the material hung thereon 70 in vertical motion, so that while the hanging-roller-conveyer and the conveyer-platform are moving slowly along the machine, the material is working its way ahead along the rollers from one to the other at a very 75 much faster rate of speed, and can be regulated to run at any desired speed, so that each portion of the material, which is in the first instance hung over a particular supporting roller in the machine when the 80 same is first introduced therein, keeps working its way along from roller to roller successively until it reaches the position indicated by the end drop 56, Figs. 1, 3 and 5, at which point the same is being drawn 85 through the discharge or delivery opening 41 by the guide-rollers 42 which are geared, or otherwise suitably connected to rotate at about the same rate of speed as that assumed by the nip-rollers 33 for discharging the 90 material at the same rate of speed that the same is taken into the apparatus.

It may here be observed that the material, thus hung in the machine, is free to be acted upon by the hot air contained in the 95 same, and is kept continually in motion throughout the machine without being subjected to tension, as is the case when resorting to the ordinary cylinder drying method, which furnishes forced drying and keeps 100 the cloths at all times subjected to tension, resulting in imperfectly treating the material, allowing creasing and tendering of the same, and only producing a surface and superficial dye which cannot remain fast 105 and permanent; while in my machine, it will be observed that the dimensions thereof may be made to suit, the idea being to provide a machine of considerable length and height, so that the same will be able to accommodate 110 and house a large amount of material, and so that each and every part and section of the draft of material housed in the machine will be subjected to the hot air drying from the time that it is first introduced into the 115 machine until it is discharged therefrom; thus allowing the same ample time to permit positive drying and oxidation in the interim, thereby affording the material an opportunity to be subjected to a natural drying 120 which is not forced, as in the case of the cylinder drying referred to above in the art, and at the same time is relieved of the objectionable tension feature which is inherent in the cylinder drying process.

The machine is very simple in construction, easy to operate, and requires very little attendance, and can be designed to handle great quantities of material,—the same being especially useful for employment in connec- 130

tion with the so-called anilin black dyeing, wherein the trade resorts to the use of cylinder drying which is a forced drying, keeping the materials at all times under tension, 5 and which has been proven to produce poor results, inasmuch as it weakens the material and tenderizes it, destroys the luster of the fiber and only furnishes it with a surface and superficial dye which soon rubs off and 10 permits the material to turn green.

The machine as I claim it, is particularly applicable to be used in drying silks and silk and cotton mixtures, as well as cottons, at the low temperature that is required to get 15 the silk to take the dye at the one bath, since the cotton is given a much better opportunity to dry in my machine,—the same being subjected therein to the air drying influence a greater length of time than it is afforded 20 when subjected to the forced cylinder drying; therefore the cotton is enabled to dry at a reasonably low temperature, such as may be required for drying the silk. Any desired temperature of hot air may be introduced 25 into the machine at any desired velocity to suit the peculiar conditions of the particular material passing through the same and being treated therein.

It must be observed that the machine permits 30 the material to run straight and wide without any chance of causing breakouts, or tapes, or tender places which are brought on in cylinder drying, especially when stopping the cylinders from rotating for any 35 purpose. The speed of the material may be maintained at a much higher speed than can be had in cylinder drying, and because the goods within the machine is hung free and without tension upon it and is thoroughly 40 surrounded by hot air which is blown directly against it from all sides, a natural drying operation is thereby produced, which assures permanent results so far as the condition of the dye is concerned, and also, since 45 the machine may take and treat material coming from a single padding machine direct into the heating chamber, a saving of dyeing liquor will naturally result therefrom.

It is suggested that the machine be of a 50 sufficient length and the various apparatus thereof be timed to operate at a rate of speed which will keep the material in transit therein and subjected to hot air drying approximately about one-half hour, for producing best results,—it being understood that the longer the dimension of the machine and the higher the same is built, the more material may be handled within it, and that 55 two drafts of material can be handled as readily as a single draft, the two drafts coming through the machine simultaneously. The mechanism involved is of the simplest nature and the parts thereof are not complicated but are simple and substantial and 60

need not be expected to cause trouble, the same being made of suitable material to withstand conditions to which they are subjected.

It will also be observed that by properly 70 timing and regulating the speed of the various turning members of the device, any desired result, so far as output is concerned, may be accomplished,—the machine at all times assuring the material treated therein 75 of a fast and lustrous dye, free from creases, breakouts or tapes and tender parts.

While the preferred embodiments of my 80 invention have been described in detail, it will be understood that I do not wish to be limited to the particular construction set forth, since various changes in the form, material, proportions and arrangement of parts, and in the details of construction may be resorted to without departing from the spirit 85 and scope of the invention, or destroying any of the advantages contained in the same, heretofore described and defined in the subjoined claims.

What I claim is:—

1. A machine for drying fabrics in open 90 form, consisting of an inclosed casing provided with an inlet and outlet for the material; combination roller-hanging and conveying means adapted to convey the fabrics through the machine to and through the delivery end thereof; transferring means adapted to guide the fabrics upon the successive hanger and conveyer rollers of said combination roller-hanging and conveying 95 means; means for supplying a drying medium within the machine, the same being provided with an inlet and outlet therefor; and a supporting conveyer-platform at the bottom of the machine for carrying and conveying the surplus hangings of the fabrics hung on the aforesaid roller-hanging and conveyer member for conveying the same 100 through the machine therewith.

2. A machine for drying textile fabrics 110 in open form, consisting of the inclosed casing member supplied with circulating hot air therein and provided with a conveyer member operating therein for hanging the fabrics thereon and keeping the same in vertical motion and for laterally conveying the hangings of fabrics simultaneously through the machine; and a conveying-platform adapted to support the surplus hangings of the material hung on the aforesaid conveying 115 member for laterally conveying them along with the aforesaid conveyer member through the machine.

3. A machine for drying fabrics in open 120 form, consisting of an inclosed casing provided with an inlet and outlet for the material; combination roller-hanging and conveying means adapted to convey the fabrics through the machine to and through the delivery end thereof; transferring means 125

90

100

105

110

115

120

125

130

adapted to guide the fabrics upon the successive hanger and conveyer-rollers; means for supplying a drying circulating medium within the machine, the same being provided with an inlet and outlet therefor; a supporting conveyer-platform at the bottom of the machine for carrying and conveying the surplus hangings of the fabrics hung on the aforesaid roller-hanging and conveyer member for conveying the same through the machine therewith; and means for operating said conveyer-platform and said hanger conveyer simultaneously.

4. A machine for drying textile fabrics in open form, consisting of an inclosed casing member supplied with a continuous charge of circulating hot air therein and provided with an endless conveyer member having a plurality of transverse and parallel 20 rotatable hanging members adapted to rotate thereon simultaneously with being laterally conveyed within said inclosed casing member for hanging material thereon and conveying the same through the machine.

25 5. A machine for drying textile fabrics in open form, consisting of an inclosed casing member provided with an inlet and outlet for the material; means for drawing in the material into the said inclosed casing; means for shiftingly hanging said material and frictionally advancing the same thereon and at the same time conveying said hangings laterally to the outlet end of the machine; and means for supplying the hot 30 air medium within the inclosed casing of the machine for making contact with the material contained therein.

6. A machine for drying textile fabrics in open form, consisting of an inclosed casing member provided with an inlet and a delivery outlet for the materials; rotatably mounted and laterally moving hanger conveyer means adapted to shiftingly hang material thereon in layers and to keep the 40 same in lateral motion toward the delivery end of the machine; auxiliary conveying means for conveying the surplus hangings at the bottom of the machine along with the aforesaid conveyer in the direction thereof; and means for circulating the drying medium within the machine for influencing the material contained therein.

7. A machine for drying textile fabrics in open form, consisting of an inclosed casing member provided with an inlet and outlet for the material; means for drawing in the material into the said inclosed casing; means for hanging said material and conveying said hangings to the outlet end of the machine; means for distributing the material upon the hanging members of said hanging and conveying means; means for supplying the hot air medium within the inclosed casing of the machine for making contact with the material contained therein; and means

for supporting and conveying the surplus hangings carried by said hanging and conveying means for conveying the same through the machine therewith.

8. A machine for drying textile fabrics in open form, consisting of an inclosed casing member provided with an inlet and outlet for the material; means for drawing in the material into the said inclosed casing; means for hanging said material and conveying 75 said hangings to the outlet end of the machine; means for distributing the material upon the hanging members of said hanging and conveying means; means for supplying the hot air medium within the inclosed casing of the machine for making contact with the material contained therein; means for supporting and conveying the surplus hangings carried by said hanging and conveying means for conveying the same through the 80 machine therethrough; means for operating said drawing means; means for operating said hot air supply; means for operating said supporting and conveying platform; and means for operating all of the aforesaid 85 operating means.

9. A machine for drying textile fabrics in open form, consisting of an inclosed casing member provided with an inlet and a delivery outlet for the materials; hanger conveyer means adapted to hang material thereon in layers and to keep the same in motion over said hangers and along with the same in its direction of travel toward the delivery end of the machine; means for conveying the surplus hangings at the bottom of the machine along with the aforesaid conveyer in the lateral direction thereof; and means for circulating the drying medium within the machine for influencing the 100 material contained therein.

10. A machine for drying textile fabrics in open form, consisting of an inclosed casing member provided with an inlet and a delivery outlet for the materials; hanger conveyer means adapted to hang material thereon in layers and to keep the same in motion over said hangers and along with the same in the direction of travel toward the delivery end of the machine; means for operating said hanger conveyer means; auxiliary conveying means for conveying the surplus hangings at the bottom of the machine along with the aforesaid conveyer the direction thereof; means for operating 110 said auxiliary conveying means; and means for circulating the drying medium within the machine for influencing the material contained therein.

11. A machine for drying textile fabrics 115 in open form, consisting of an inclosed casing member provided with an inlet and a delivery outlet for the materials; means for drawing in material into the machine; means for operating said material-drawing 120

130

means; hanger-conveyer means adapted to hang material thereon in layers and to keep the same in motion over said hangers and along with the same in the direction of travel toward the delivery end of the machine; distributing means adapted to hang the material over the hanger members of said hanger-conveyer means; means for operating said hanger-conveyer means; auxiliary conveying means for conveying the surplus hangings at the bottom of the machine along with the aforesaid conveyer in the direction thereof; means for operating said auxiliary conveyer means; and means for circulating the drying medium within the machine for influencing the material contained therein.

12. A machine for drying textile fabrics in open form, consisting of an inclosed casing member provided with an inlet and an outlet for receiving and delivering the material; means for supplying the same with a drying medium; means for drawing in the material into the said inclosed casing; an endless conveyer consisting of a plurality

of transverse and parallel hanging-rollers 25 rotatably mounted thereon and adapted to be carried around the machine and to support fabrics entering the same when reaching the top position in the machine; means for operating said conveyer member for conveying the rollers laterally; means for independently rotating said laterally conveyed hanging-rollers for frictionally leading and advancing the fabrics supported thereon; means for guiding and hanging the fabrics 35 entering the machine on the successive rollers of the conveyer member; auxiliary conveyer means for supporting the bottom and surplus hangings of the fabrics hung on said hanging-rollers for advancing the same 40 along the machine laterally in the direction of the aforesaid conveyer member; means for operating said auxiliary conveyer means; and means for withdrawing the material from within the machine through the delivery end thereof. 45
